ADJUSTABLE FRAME FOR DOOR LOUVERS

Richard W. Graham, Williamstown, W. Va., assignor to
The Airolite Company, Marietta, Ohio, a corporation
of Ohio

Filed Apr. 5, 1966, Ser. No. 1,783

Term of patent 14 years

(Cl. D13—1)

FIG. 4

FIG. 5

FIG. 6

FIG. 1 is a top plan view of an adjustable frame for door louvers embodying my new design;

FIG. 2 is an elevational view thereof;

FIG. 3 is an elevational view thereof, as viewed from an opposite side of FIG. 2;

FIG. 4 is a sectional view taken as on line 4-4 in FIG. 3;

FIG. 5 is a sectional view taken as on line 5-5 in FIG. 6; and

FIG. 6 is an elevational view of a modified embodiment of the design of the present invention.

The dotted lines shown in the several views are for illustrative purposes only.

I claim:

The ornamental design for an adjustable frame for door louvers, as shown and described.
